FRUIT SPOON OR THE LIKE

Charles P. Schiller, Winter Haven, Fla.

Application October 10, 1956, Serial No. 43,297

Term of patent 14 years

(Cl. D54—12)

Fig. 1

Fig. 2

Fig. 3

Fig. 4

Figure 1 is a top plan view of a fruit spoon or the like embodying my new design;

I claim:

The ornamental design for a fruit spoon or the like, as shown.
